US00D994009S

(12) **United States Design Patent** (10) **Patent No.:** **US D994,009 S**
Cheng (45) **Date of Patent:** **** Aug. 1, 2023**

(54) **TRI-SENSOR CAMERA**

(71) Applicants: **GUANGZHOU SHIYUAN ELECTRONICS CO., LTD.**
Guangdong (CN); **GUANGZHOU SHIRUI ELECTRONICS CO., LTD.**
Guangdong (CN)

(72) Inventor: **Biliang Cheng**, Guangdong (CN)

(73) Assignees: **GUANGZHOU SHIYUAN ELECTRONICS CO., LTD.**
Guangdong (CN); **GUANGZHOU SHIRUI ELECTRONICS CO., LTD.**
Guangdong (CN)

(**) Term: **15 Years**

(21) Appl. No.: **29/773,567**

(22) Filed: **Mar. 10, 2021**

(30) **Foreign Application Priority Data**

Sep. 10, 2020 (CN) 202030535936.0

(57) **CLAIM**

The ornamental design for a tri-sensor camera, as shown and described.

DESCRIPTION

FIG. 1 is a front view of the tri-sensor camera showing my new design;

FIG. 2 is a rear view of the thereof;

FIG. 3 is a left side view of the thereof;

FIG. 4 is a right side view of the thereof;

FIG. 5 is a top view of the thereof;

FIG. 6 is a bottom view of the thereof;

FIG. 7 is a perspective view of the tri-sensor camera;

FIG. 8 is another perspective view of the tri-sensor camera thereof; and,

FIG. 9 is another perspective view of the tri-sensor camera thereof in a state of use.

1 Claim, 9 Drawing Sheets
